UNITED STATES PATENT OFFICE.

EUGEN PRESTINARI, OF IRVINGTON, NEW JERSEY, ASSIGNOR TO NEW JERSEY CHAIN CORPORATION, OF NEWARK, NEW JERSEY, A CORPORATION OF NEW JERSEY.

BRACELET CHAIN.

Application filed November 10, 1927. Serial No. 232,427.

This invention relates to an improved construction of chain or bracelet formed of a plurality of extendible links; and the object of this invention is to construct such a chain or bracelet having outer or guide links formed of sheet stock with inturned portions at one end formed to receive laterally-extending hook ends of the slide link in the next adjacent guide link, the entrance of said hook members of the slide link into engagement with said hook receiving members of the guide link being controlled by a depressible end portion of the rear wall of the guide link.

5 A further object of the invention is the forming of a guide link with front, rear and side walls, a portion of the rear wall being depressible and the edges of the side walls being turned over those of the rear wall to prevent the latter from being raised or moved outwardly relative to the front wall thereof.

A still further object of the invention is the forming of inwardly turned end portions on one of the walls of the guide link forming 25 hook-receiving pockets and providing the co-operating slide link with laterally-extending hook portions arranged to enter and leave said pockets only when the entrance control end of the rear wall is depressed.

30 With these and other objects in view, the invention consists of certain novel features of construction, as will be more fully described, and particularly pointed out in the appended claims.

35 In the accompanying drawings:

Figure 1 shows a plurality of links of a section of chain of my improved construction with the links in extended position, one of the links being broken away to show the arrangement of parts and the compressible spring 40 acting upon the guide and slide links.

Figure 2 is a perspective view of the guide link showing the same in partially closed position.

45 Figure 3 is a perspective view of the slide link.

Figure 4 shows the slide link as mounted in the guide link, the guide link being in partially folded position.

50 Figure 5 shows the guide link in folded position with the hook end of the slide link extending therefrom.

Figure 6 is a perspective view showing the hook end of the slide link as extending from the guide link and also showing one end of

the rear wall of the guide link as being depressed to receive the hook ends of the next adjacent slide link.

Figure 7 shows the slide link of the next adjacent unit with its hook ends entering the hook receiving pockets of the guide link.

Figure 8 shows the two link units as hooked together, one of the guide links being partly in section.

Figure 9 is a plan view partly in section showing the hook ends of the slide link as engaging the inturned edges of the next adjacent guide link also showing the spring in one of the link units.

It is found in the practical construction and operation of chains of this character of advantage to provide link units which comprise a guide link of the box type in which is mounted a slide link of frame shape and to provide means at one end of the guide link to receive laterally-extending hook-shaped members of the next adjacent slide link and to control the entrance of the hooks to the hook-engaging members by the depressible rear wall of the guide link whereby the links may be readily connected and disconnected from each other to adjust the operating length of the chain and also to remove any single link unit that may be out of repair without disturbing the other units of the chain; and the following is a detailed description of the present embodiment of my invention and showing one arrangement of chain links by which these advantageous results may be accomplished:

With reference to the drawings, 10 designates the guide link which is formed from sheet stock into the desired box form so that it may be folded to provide a front wall 11, side walls 12 and a rear wall 13. This rear wall is connected at one end to the front wall by means of a narrow neck portion 14 and the side edges 15 of this rear wall are slightly depressed or offset inwardly from the plane of the rear wall to receive the inturned edges 16 of the side walls, which inturned edges serve to prevent the free end of the rear wall from an opening movement or a movement away from the front wall permitting this free end of the rear wall a free inward or depressing movement for the purpose presently described.

The end of this guide link opposite the connecting neck portion 14 is provided with in-turned members or fingers 17 preferably

formed integral with the ends of the side walls 12, these inturned portions being somewhat in arcuate shape forming pockets 18 for the reception of the laterally extending hook ends 19 of the frame-shaped slide link 20 which is mounted to slide endways in each of the guide links.

The side arms 21 of this frame-shaped slide link straddle the narrow neck portion 14 and the inner ends 22 of this slide link are connected by a cross bar 23 which serves as an abutment for the compression spring 24 which is arranged to act between this cross bar 23 and the neck member 14.

In assembling these parts the side arms 21 of the frame shaped slide link are passed inwardly to straddle the neck portion 14 of the guide link and the dovetailed ends of the cross bar 23 are then positioned and secured between these side arms. A compression spring 24 is then inserted to act upon the neck member 14 and this cross bar 23. Next the rear wall 13 is folded down into position illustrated in Figure 8 and the edges 16 of the side walls 12 are folded over the depressed edges 15 of this rear wall thereby bringing the edges 16 flush with the plane of the middle portion of this rear wall leaving the unattached end 25 of this rear wall free to be depressed inwardly towards the front wall, the inturned edges 16 preventing it from being opened outwardly and thus the unit is complete.

In assembling the different units, it is only necessary to draw outwardly the hook end of the slide link, depress the free end 25 of its rear wall and pass these hook ends 19 into engagement with the inturned members 17 of the next adjacent guide link and the units are connected together.

My improved construction is very simple and practical to manufacture and assemble and is very handsome and attractive in appearance when the units are connected into a general formation.

The foregoing description is directed solely towards the construction illustrated, but I desire it to be understood that I reserve the privilege of resorting to all the mechanical changes to which the device is susceptible, the invention being defined and limited only by the terms of the appended claims.

I claim:

1. A bracelet chain structure comprising a series of extendible link units each having a guide link formed of sheet stock folded to provide front, rear and side walls and a narrow connecting neck portion forming part of one end wall, portions of the side walls of the opposite end of the guide link being folded inwardly providing hook-receiving pockets, one end of said rear wall

being depressible and arranged to control the entrance to said hook-receiving pockets to permit the passage of the hooks to and from said pockets and a slide link in said guide link having laterally extending hook portions shaped to enter and leave said pockets in the next adjacent guide link when the rear wall thereof is depressed.

2. A bracelet chain structure comprising a series of extendible link units each having a guide link formed of sheet stock folded to provide front, rear and side walls and a narrow connecting neck portion forming part of one end wall, portions of walls at the opposite end of the guide link being folded inwardly providing hook-receiving pockets, one end of said rear wall being depressible and arranged to control the entrance to said hook-receiving pockets, a slide link in said guide link having laterally-extending hook portions shaped to enter and leave said pockets in the next adjacent guide link when the rear wall thereof is depressed, and means for preventing the depressible end of said rear wall from being raised from its normal plane.

3. A bracelet chain structure comprising a series of extendible link units each having a guide link formed of sheet stock folded to provide front and side walls and a rear wall depressible at one end, the edges of the side walls being folded over those of the rear wall securing the latter against a movement away from the front wall, an integral neck portion connecting one end of the front and rear walls, portions of the walls at the opposite end of this link being folded inwardly forming hook-engaging members, and a slide link in said guide link having laterally-extending hook portions shaped to engage said engaging members in the next adjacent guide link only when said rear wall thereof is depressed.

4. A bracelet chain structure comprising a series of extendible link units each having a guide link formed of sheet stock folded to provide front, rear and side walls and a narrow connecting neck portion forming part of one end wall, portions of the side walls at the opposite end of the guide link being folded inwardly providing hook-receiving pockets, one end of said rear wall being depressible and arranged to control the entrance to said hook-receiving pockets, a slide link in said guide link having laterally-extending hook portions shaped to enter and leave said pockets in the next adjacent guide link when the rear wall thereof is depressed, and the edges of said side walls being turned inwardly over those of said rear wall to prevent the depressible end of said rear wall from being raised from its normal plane.

In testimony whereof I affix my signature.
EUGEN PRESTINARI.
